(57) **CLAIM**

The ornamental design for an electronic drum pad, as shown and described.

DESCRIPTION

FIG. 1 is a perspective view of the front, top and right side of an electronic drum pad according to a first embodiment showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a perspective view of the front, top and right side of an electronic drum pad according to a second embodiment showing my new design;

FIG. 9 is a front view thereof;

FIG. 10 is a rear view thereof;

FIG. 11 is a left side view thereof;

FIG. 12 is a right side view thereof

FIG. 13 is a top plan view thereof; and,

FIG. 14 is a bottom view thereof.

The broken line showing of the electronic drum pad is included for the purpose of illustrating portions of the electronic drum pad and forms no part of the claimed design.
